UNITED STATES PATENT OFFICE

TOKUZO NISHIMURA, OF TOYOTAMA GUN, TOKYO FU, JAPAN

PORTABLE AUTOMATIC PENCIL SHARPENER

Application filed December 9, 1929, Serial No. 412,856, and in Japan December 14, 1928.

The present invention relates to a portable automatic pencil sharpener, wherein a screw cutter is rotatably mounted adjacent a hollow conical part connected with a hollow cylindrical bushing; a cylindrical pencil holder having the splits up to near its end is inserted in the bushing through a toothed wheel at its rear end; keys projecting in the interior of said wheel engage with said splits; a toothed wheel is geared between said wheel and the wheel at the rear end of the cutter, toothed wheel being provided with a hand crank; the pencil holder and the cutter are connected together in such a manner that each rotates around its own axis simultaneously in the same direction, the holder being also slidable vertically; and a clamp is screwed to the end of the holder so that the pencil is clamped by it and pressed gradually into the bushing together with the holder as it is sharpened. The object of this invention is to obtain such a portable and durable pencil sharpener that it sharpens the pencil automatically and neatly only by holding it with one hand and rotating the crank with the other hand and accordingly can be used easily even by little children.

Referring to the accompanying drawings, Figure 1 is the longitudinal side view of the pencil sharpener according to this invention;

Figure 2, the front view having no pencil;

Figure 3, the enlarged longitudinal side view of the pencil holder;

Figure 4, is a sectional view on line 4—4 of Fig. 1 and

Figure 5, the side view partly in section of the modification of the present invention.

In the drawings, 1 is a bushing consisting of a hollow cylindrical body and a hollow conical body. A screw cutter 2 is rotatably mounted adjacent the longitudinally-split outside of the conical part of the sheath by means of metal pieces 3 and 4 and has a toothed wheel 5 upon its upper end for rotating it. In the bushing there is inserted through a toothed wheel 8 at its rear end a cylindrical pencil holder 6 which can slide in contact with the interior wall of the bush-

ing 1 and which have the splits 7 cut vertically from near its top to the bottom. These splits 7 assist the holder 6 in clamping the pencil and also engage with keys 9 projecting in the interior of the wheel 8, so that the holder 6 may rotate according to the revolution of the wheel 8, when it may also be able to slide vertically along the keys 9 in the bushing. The end of the holder 6 has an inclined surface 6' (Fig. 3) and has a screw threaded part in connection with this inclination. To this part is fixed a clamp 10, a grip 11 is attached rotatably which has a clasp 12 to prevent it from getting out. Also, a toothed wheel 14 is provided at one side of the bushing 1, and it is engaged with the toothed wheels 5. Therefore, the cutter and holder rotate simultaneously in the same direction and consequently the contact parts of the cutter and pencil rub each other in the opposite direction. 16 is a piece for preventing the wheel 8 from moving vertically along with the holder and has it fixed to the side of the bushing 1. The cutter has a cover 18 of suitable material so as to facilitate the grasping of the sharpener on the palm. Said cover may have an enlarged end having a lid 19 which is opened when it is desired to take out the chips accumulated in the enlarged part.

In this invention two cutters may be fixed oppositely to the conical part of the bushing 1. In this case, a toothed wheel 5 is provided at one end of each cutter so that it engages with two wheels 14 both being geared with a toothed wheel.

The following is the manner of using this article:—

First draw out the holder 6 slightly from the bushing 1, loosen the clamp 10 and insert a pencil deeply enough thereinto, after which the clamp is tightened. Then, put the cover 18 on the palm of the left hand and support the grip 11 with the thumb and the forefinger, grasping the bushing and cutter, and turn the crank with the right hand, pressing the holder toward the bushing 1 with the left hand. As regards the sharpener shown in Figure 5, turn its end toward the thumb of the left hand and grasp the bushing and cutter, and, sup-

port the grip 11 with the little finger and turn the handle with the right hand, pressing with the thumb of the left hand the edge of the metal piece 4 at the end of the cutter. Then, 5 the pencil and cutter will rotate simultaneously in the same direction according to the rotation of the crank, whereby the contact parts of the pencil and cutter rub each other in the opposite direction and the pencil can be 10 pressed gradually into the bushing during sharpening thereof. Thus, the point of the pencil can be sharpened neatly in conical shape.

There is the sharpener to which the screw 15 cutter is applied, but according to the present invention the whole sharpener including the cutter can be grasped on the palm and the cutter can be rotated in that position. If you simply hold it with the left hand and turn 20 the crank with the right hand, pressing the grip and sheath with the left hand, the pencil will be sharpened neatly and rapidly, even by little children.

Claims:

25 1. In a pencil sharpener, the combination of a rotary cutter having a toothed wheel connected therewith, a bushing fixed adjacent the cutter, a pencil holder slidable in the bushing and having longitudinal slits therein, a 30 wheel on the holder having keys carried thereby, for slidably engaging the slots to permit sliding of the holder in the bushing during the sharpening operation, a wheel in mesh with the first mentioned wheel, and a crank 35 for rotating the latter wheel to impart rotary movement to the wheels and to the holder.

2. In a pencil sharpener, the combination of a rotary cutter, a bushing adjacent the cutter, a pencil holder having longitudinal slits 40 therein, a toothed wheel having a central opening receiving the holder, keys extending into the opening and engaged in said slits to slidably interlock the wheel and holder to permit the holder to move vertically in the 45 bushing during rotation of the cutter, and means for simultaneously rotating the wheel and cutter.

In testimony whereof, I have signed my name to this specification at Tokyo, Japan, 50 this 18th day of November, 1929.

TOKUZO NISHIMURA.
